(57) CLAIM

The ornamental design for a wearable hooded towel, as shown and described.

DESCRIPTION

FIG. 1 is a front perspective of the hooded portion of the wearable hooded towel showing my new design;

FIG. 2 is a rear perspective view thereof;

FIG. 3 is a top plan view thereof;

FIG. 4 is a front elevation thereof;

FIG. 5 is a right side elevation view thereof;

FIG. 6 is a left side elevation view thereof;

FIG. 7 is a rear elevation view thereof; and,

FIG. 8 is a bottom plan view thereof.

The broken lines in FIG. 1 represent a portion of the human form showing the wearable hooded towel form no part of the claimed. The broken lines showing the text in FIGS. 2, 5, 6, and 7 are included for the purpose of illustrating environmental structure and form no part of the claimed design.
